UNITED STATES PATENT OFFICE.

CHRYSSTAL CHRISTOPHER McCUE, OF GOODELLS, MICHIGAN.

FOUNTAIN PEN.

Application filed October 23, 1928. Serial No. 314,347.

The present invention relates to improvements in fountain pens and has for its principal object to provide a fountain pen that may be readily and easily filled with only one stroke of the sliding plunger that is employed for refilling the pen.

A further object is to provide a fountain pen that does not employ the usual rubber bag or sack, thus prolonging the life of the pen and further enabling a maximum amount of ink to be retained in the barrel.

A further object is to provide a fountain pen of the above mentioned character that includes means for releasing the air in the barrel for breaking the suction therein caused during the filling of the pen upon the upstroke movement of the plunger.

A further object is to provide a pen of the above mentioned character that is simple in construction, inexpensive, strong and durable and further well adapted to the purposes for which it is designed.

Other objects and advantages will become apparent during the course of the following description.

In the accompanying drawing, forming a part of this specification, and in which like numerals indicate like parts throughout the same:

Figure 1 is a longitudinal sectional view through the fountain pen embodying my invention,

Figure 2 is a transverse section taken upon the line 2—2 of Figure 1 looking upwardly, and

Figure 3 is a similar section taken approximately on the line 3—3 of the same figure looking downwardly.

In the drawing wherein for the purpose of illustration is shown the preferred embodiment of my invention, the numeral 1 designates the cylindrical barrel that is open at its respective ends.

A substantially cup-shaped head 2 is threaded at its upper end within the lower end of the barrel and this head is formed in its closed lower end with the central ink feed passage 3 for supplying ink from the barrel to the nib 4 in the usual manner.

The lower closed end of the cup-shaped head 2 is furthermore formed with a through passage 5 and a check valve 6 is arranged in the upper end of the passage as clearly shown in Figure 1. This check valve normally is disposed in a closed position to prevent the escape of the ink through the

passage 5 but is adapted to be opened under the suction created in the barrel by the sliding plunger during the filling operation of the fountain pen in the manner to be presently described.

This check valve is limited in its upward movement by reason of a pin and slot connection as is also clearly indicated in Figure 1.

The upper end of the bore of the barrel 1 is reduced whereby to form the shoulder 7 for a purpose to be presently described and the lower end portion of the reduced upper end of the bore is threaded as suggested very clearly in Figure 1.

Forming a salient part of the present invention is the tubular plunger rod 8 that is arranged for slidable movement within the upper portion of the barrel and formed on the lower end of the tubular plunger rod is the piston 9 that frictionally engages with the inner wall of the cylindrical barrel 1.

The piston is formed with a central air escape opening 10 and the upper end of this opening is enlarged to form a concaved seat 11 for a purpose to be presently described.

The plunger or piston rod 8 is externally threaded adjacent the piston 9 for cooperation with the internally threaded portion 18 of the reduced portion of the bore of the barrel for maintaining the piston in its uppermost position within the barrel against the shoulder 7.

The upper end of the tubular plunger or piston rod 8 is internally threaded for receiving the externally threaded sleeve 12 formed on the bottom of the solid head 13 that provides a closure for the open upper end of the tubular piston rod. Depending from the bottom of the central portion of this solid head 13 and extending throughout the length of the tubular piston rod is the elongated pin 14, the lower end thereof being slightly rounded for cooperation with the seat 11 formed at the upper end of the air escape opening 10.

The upper end portion of the tubular piston or plunger rod 8 is formed in its side with an air escape opening 15 and the sleeve 12 is formed with a similar opening 16 for cooperation therewith. The usual cap that is removably secured over the point of the fountain pen is shown at 17 and the same is detachably secured on the lower end of the barrel 1.

When the parts are arranged as shown

in Figure 1, it will be observed that the lower end of the elongated pin 14 is positioned in the seat 11 thus cutting off communication between the piston rod 8 and the barrel 1. The openings 16 and 15 will be out of communication with each other and the piston 9 will be disposed in the upper portion of the barrel against the shoulder 7.

Prior to the filling of the pen, the cap 10 is removed and the piston rod is disconnected from the threaded portion 18 of the barrel after which said piston rod is forced downwardly in the barrel to position the piston 9 against the bottom of the cup shaped head 2.

The nib of the pen is then immersed into a bottle of ink or inkwell so that the head 2 is submerged. The piston rod 8 is then moved upwardly through the upper open end 20 of the barrel causing the upward movement of the piston 9 in said barrel and this movement will create a suction in the barrel to raise the valve 6 out of its operative position and simultaneously draw in a quantity 25 of ink into the barrel.

After the piston has reached the end of its uppermost movement so that said piston strikes the shoulder, the piston rod is rotated in the reverse direction to secure said piston rod against vertical movement and to further maintain the piston against the shoulder.

The solid head 13 is then actuated to rotate the sleeve whereby to bring the opening 16 into registration with the opening 15 and simultaneously the lower end of the elongated pin 14 will be moved out of engagement with the seat 11 and the vacuum created in the barrel will be released. When 40 the vacuum is broken, the head 13 is again actuated to move the openings 15 and 16 out of registration with each other and at the same time, the lower rounded end of the pin 14 will rest in the seat 11 and thus prevent the admittance of air under pressure to the barrel.

The ink will flow from the barrel to the nib 4 through the passage 3 during the use 50 of the pen when writing in the usual manner.

It will thus be seen from the foregoing description, that I have provided a fountain pen that will obviate the necessity of having to employ the conventional rubber 55 sack or bag and thus the life of the pen is prolonged and also a maximum amount of ink may be carried by the barrel.

Furthermore my improved fountain pen, is of such construction as to permit the 60 same to be readily and easily operated for re-

filling the same whenever necessary and the pen will not leak.

While I have shown the preferred embodiment of my invention, it is to be understood that various changes in the size, shape and arrangement of parts may be resorted to without departing from the spirit of the invention and the scope of the appended claims.

Having thus described my invention, what I claim as new is:

1. In a fountain pen, a barrel, a conventional nib associated with the lower end of the barrel for receiving the ink therefrom, the lower end of the barrel being formed 75 with an inlet, a check valve for said inlet opened under suction created in the barrel, a piston rod operable through the upper end of the barrel, a piston carried by the lower end of the piston rod, said piston adapted to 80 create a suction in the barrel for filling the same upon the upstroke of the piston rod, means for limiting the upward movement of the piston in the barrel, additional means for securing the piston in its raised position, 85 said last mentioned means comprising external threads formed on the lower end portion of the piston rod above the piston, the upper end portion of the bore of the barrel being threaded for cooperation with the threads on 90 the piston rod.

2. In a fountain pen, a barrel, a conventional nib associated with the lower end of the barrel for receiving the ink therefrom, the lower end of the barrel being formed 95 with an ink inlet passage, a check valve for said passage opened under suction created in the barrel during the filling of the pen, a tubular piston rod arranged for slidble movement through the upper end of the barrel, a piston carried by the lower end of the piston rod for operation within the barrel, said piston creating a suction in the barrel to fill the same when the piston rod is moved upwardly through the upper end of the barrel, said piston being formed with a central air passage, a head secured on the upper end of the tubular piston rod for vertical movement, an elongated pin carried by the head and extending downwardly in the 100 tubular piston rod, the lower end of said pin adapted to be positioned over the upper end of the opening in the piston when said head is in its lowermost position, said head and the tubular piston rod being formed with air 105 openings adapted to register with each other when the head is in its raised position for the purpose described.

In testimony whereof I affix my signature.

CHRYSSTAL CHRISTOPHER McCUE.
